CHARLES W. JEFFRIES, OF LAKE CHARLES, LOUISIANA, ASSIGNOR OF ONE-FOURTH TO
MASON P. ERWIN, OF LAKE CHARLES, LOUISIANA

SYNCHRONIZING SYSTEM FOR TELEVISION APPARATUS

Application filed October 23, 1929. Serial No. 401,779.

The invention relates to television apparatus and has particular reference to means for synchronizing the speed of rotation of the scanning disc of a receiver with that of a transmitter.

The principal object of the invention, generally speaking, is to provide in a television apparatus means whereby to obtain an absolute and perfect synchronization of the scanning disc of the receiver with respect to the rotation of the scanning disc of the transmitter, this being an essential feature in the operation.

It is well known that in television apparatus it is customary to make use in the transmission system of a disc provided with a spirally arranged series of holes cooperating with or disposed between a source of light, properly shielded, and a photoelectric cell, and it is also well known that in the receiving apparatus it is customary to provide a similar disc having a spiral series of holes or perforations therein interposed between the screen and a neon tube which is responsive to variations in the photoelectric cell of the transmitting apparatus. It is also known that it is absolutely necessary to have the scanning disc of the transmitting apparatus in perfect synchronism or timing with that of the receiving apparatus as otherwise the light graduations or gradations or other fluctuations or variations would not be visible so that the entire apparatus would fail.

A more specific object of the invention is to provide in a television apparatus or system a scanning disc having an auxiliary perforation or hole therein provided for the sole purpose of cooperating with the source of light and the photoelectric cell or neon tube, as the case may be, for the purpose of effecting the synchronization of the motors which drive the scanning discs of the transmitting and receiving apparatus.

A further object is to provide in a system of this character a synchronizing means which will be fixed and which may not necessarily be a part of or provided with the scanning disc itself but which may be formed as an adjunct as for example in an auxiliary disc

mounted on the same shaft which carries or drives the scanning disc.

Another object is to provide means of the character specified and for the purpose set forth which will not in any way interfere with the usual arrangement but which embodies only a few parts which may be added easily and which will operate to control a relay and resistance means interposed in the circuit of the motor of the receiver, which motor drives the scanning disc, whereby the speed of rotation of the motor armature and consequently the scanning disc will be exactly synchronized with the rotation of the scanning disc of the transmitter.

An additional object is to provide an apparatus of this character which will be simple and inexpensive to make, assemble or install, positive in action, efficient and durable in service, and a general improvement in the art.

With the above and other objects and advantages in view, the invention preferably consists in the details of construction and the arrangement and combination of parts to be hereinafter more fully described and claimed, and illustrated in the accompanying drawings, in which:

Figure 1 is a partial perspective and partial diagrammatic view illustrating the transmitting apparatus.

Figure 2 is a similar view of the receiving apparatus.

Figure 3 is a detail view of the receiving apparatus showing the relative location of the tubes with respect to the auxiliary or synchronizing aperture disc.

Referring more particularly to the drawings, Figure 1 illustrates diagrammatically a television transmitting set or apparatus in which there is a source of light 10 adapted to project rays through an aperture 11 in a screen 12, the rays falling onto and being adapted to pass through a spiral series of perforations 13 in a scanning disc 14 mounted on a shaft 15 driven by an electric motor 16. At the opposite side of the disc there is a photoelectric cell 17 connected in parallel with a plurality of photoelectric cells 18 which are connected in the transmitting system which includes the amplifiers 19 and 20, of conven-

tional design, which are in turn connected with a transmitting antenna or aerial 21. In carrying out the invention I provide the scanning disc 14 with an additional hole 22 positioned between the screen 12 or rather the aperture 11 therein and the photoelectric cell 17 which is shielded by a shield 23 so that the light falling onto this photoelectric cell 17 cannot in any way act upon the cells 18.

10 The receiving apparatus shown in Figure 2 comprises a scanning disc 24 having a spiral series of perforations 25 therein through which is adapted to be projected a ray of light from a neon tube 26, the light being thrown onto a screen 27 of the usual design. The disc 24 is represented as mounted upon a shaft 28 driven by an electric motor 29 connected with a source of current indicated by the leads 30. Interposed in one lead is a resistance 31 contacted by a movable arm 32 shown as pivoted and having an armature 33 operating between a pair of electromagnets 34 and 35 which constitute a relay device control, these magnets being connected with a suitable source of current 36 and with photoelectric cells 37 located at opposite sides of a dividing screen 38.

The essential feature in the receiving apparatus is the provision of an auxiliary disc 39 mounted upon the shaft 28 or otherwise driven with the scanning disc 24 and provided with a single aperture 40, adapted to have a ray of light pass therethrough from a neon tube 41 connected in parallel with a tube 26 so as to operate simultaneously therewith. Clearly, if such is desired, the auxiliary disc 39 with its hole 40 might be omitted and the hole 40 be provided in the scanning disc 24, there being nothing of any great importance in this variation, the whole point being that there must be the auxiliary hole 40 interposed between the tubes 37 and the tube 41.

In the operation, the time signal is received by the neon tubes 26 and 41. The first line across the screen 27 will show the time signal but this will not interfere with the balance of the lines and therefore will not in any way interfere with the picture itself. The neon tube 41 receives all the signals but as the small disc 39 has only one hole 40 therein this tube will show only the time signal through the hole to the photoelectric cells 37. When the scanning disc 24 is turning in exact relation to the transmitting disc 14, or in proper synchronization therewith, the time signal will fall evenly half and half on the photoelectric cells 37. However, should the motor 29 lag so that the disc 60 would fail to reach the proper place of time signal then the time signal will fall only on one cell 37, which cell is connected to the relay device, to increase the current to the motor by reducing the resistance by changing the position of the arm 32 upon the

coil 31. However, should the motor be too fast, the time signal will fall on the other cell 37 and increase the resistance so as to decrease the speed of the motor. This relay or resistance device is so arranged as to increase or decrease the speed of the motor in just the instant necessary to effect proper synchronization of the motor and the disc.

From the foregoing description and a study of the drawings it will be apparent that I have thus provided a very simple means whereby there will be attained a perfect synchronization of the scanning disc of the receiving apparatus with respect to the rotating disc of the transmitting apparatus. Using very sensitive relay means any small difference in the amount of light received by either of the two photoelectric cells 37 will effect the proper change in resistance in the motor circuit to synchronize everything perfectly. There is no question as to the length of time as this will be automatically compensated for at all times and for any length of time.

While I have shown and described the preferred embodiment of the invention, it should of course be understood that I reserve the right to make all such changes in the details of construction and the arrangement and combination of parts as will not depart from the spirit of the invention or the scope of the subjoined claims, as for example I may find it possible to provide the aperture 40 in the scanning disc 24 itself so as to eliminate the provision of the auxiliary disc 39. Furthermore other types of cells could be used instead of those specified without in any way departing from the invention.

Having thus described the invention, I claim:

1. In a television apparatus, a rotary receiving disc provided with a series of scanning holes, a second disc rotating with said first named disc, a motor for driving both of said discs, a screen, a neon lamp disposed at the side of the first named disc opposite the screen and adapted to receive current impulses, a second neon lamp connected in parallel with said first named neon lamp and arranged adjacent the second named disc, said second named disc having a finger hole therein for synchronizing purposes, a pair of photo-electric cells located adjacent the second named disc at the side opposite the second named neon lamp, a screen located between said pair of photo-electric cells, a resistance interposed in one of the leads to said motor, a movable arm adapted to travel over said resistance, and a pair of electro-magnets located at opposite sides of said arm and connected in parallel with a source of current and with the respective photo-electric cells for moving said arm in accordance with variations in the current to the electro-magnets in response to fluctuations caused by the beam

of light passing from the second named neon lamp through said hole onto one or the other of said photo-electric cells.

2. In a television apparatus, receiving means including a rotary disc having a synchronizing hole therein, a neon lamp arranged at one side of said disc for projecting a beam of light through said hole, said neon lamp being responsive to fluctuations of current generated at a transmitting station, a pair of photo-electric cells located at the opposite sides of said disc and having a screen interposed between them, a motor for driving said disc, and means responsive to the passage of light through said hole for controlling the speed of said motor comprising a pair of electro-magnets connected in common with a source of current and respectively connected with said photo-electric cells, a contact arm pivotally mounted and positioned to be attracted by the electro-magnets, and a resistance coil adapted to be engaged by said contact and located in series with said motor.

In testimony whereof I affix my signature.
CHARLES W. JEFFRIES.
